APPARATUS FOR HANDLING
CHIPPER KNIVES

Stanley D. Payzer, Wausau, Wis., assignor to D. J. Murray Manufacturing Co., Wausau, Wis., a corporation of Wisconsin

Application October 9, 1944; Serial No. 557,808

3 Claims. (Cl. 144—176)

1

My invention relates generally to improvements in the art of handling wood chipper knives, and relates more specifically to improved apparatus for expediting insertion and removal of the cutting blades of rotary wood chippers relative to their carrier rotors or discs.

Rotary wood chippers each comprising a rapidly revolvable disc provided with an annular series of radially disposed knives having cutting edges protruding from one side face of the disc and cooperating with a hopper for feeding logs or wood slabs at a downward inclination toward said disc face on one side of the rotor axis, have long been employed in the paper manufacturing industry. The cutting blades or knives of these machines must be frequently removed for regrinding or replacement, and while the removal and reinsertion of the blades may be a relatively simple matter in very small machines, the knives of the larger chippers are relatively heavy and bulky and extremely dangerous to handle. Then too, after the cutting blades have been in use for some time, they often become jammed within their confining openings, and can be dislodged only with great effort; and the time consumed and wasted by the prior tedious methods of manually inserting and removing such knife blades has always been a source of annoyance and expense to the operators. While the chipper knives are not readily accessible for insertion and removal at the zone of the feed hopper, free access to the cutting blades may be had on the side of the rotor axis opposite to the hopper; and although this available space remote from the hopper has heretofore been used for inserting and removing the knives, it previously was necessary to also remove various other parts of the rotor assemblages in order to apply or withdraw the cutting blades, thereby making these operations both difficult and dangerous.

It is therefore an object of my present invention to provide improved apparatus for effecting insertion and removal of the knives of rotary chippers or the like in a safe and expeditious manner, and with minimum loss of time.

Another object of the present invention is to provide new and useful instrumentalities for facilitating the rapid removal and application of chipper blades, from and to their carrier discs, without necessitating complete removal of the normal knife retaining elements of the rotor assemblage.

A further object of this invention is to provide simple and effective apparatus for quickly dislodging and removing chipper knife blades, and

2

for safely manipulating the cutting members during insertion and removal thereof.

Still another object of my invention is to provide improved apparatus for safely and expeditiously handling chipper knives or the like, so as to reduce to a minimum the danger and the time lost in reconditioning or renewing such knives.

These and other objects and advantages of the invention will be apparent from the following detailed description.

A clear conception of the several features involved in my improvement for handling chipper knives, and of the construction and operation of one type of apparatus which may be used in commercial exploitation of the invention, may be had by referring to the drawing accompanying and forming a part of this specification wherein like reference characters designate the same or similar parts in the various views.

20 Fig. 1 is a relatively large fragmentary section through a chipper rotor taken across one of the knife or blade assemblages, and showing a knife blade being forced upwardly out of its normal retaining slot and engaged by a suspension clamp or tongs;

25 Fig. 2 is a somewhat reduced side elevation of a chipper knife engaged by and suspended from one of the improved handling tongs;

30 Fig. 3 is a further reduced diagrammatic side view of a typical rotary chipper disc showing the approximate normal disposition of the radiating knives, and the relative position of the feeding hopper or spout; and

35 Fig. 4 is a perspective view of the elements used to initially force the knife blades out of their normal confining slots, in accordance with the present invention.

40 While the invention has been shown and described herein as being especially useful in conjunction with chipper knife assemblages of a particular type, it is in fact more generally applicable and it is not my desire or intent to unnecessarily restrict the scope or utility of the improvement by virtue of this specific disclosure.

45 Referring to the drawing, the rotary chipper and knife assemblage specifically shown, comprises in general a chipper rotor or rotary disc 5 mounted for rapid rotation upon a central shaft 6 and having an annular series of elongated approximately radial through openings or slots 7 therein; a chipper blade or knife 8 disposed within each of the disc openings 7, and each having a sharp cutting edge 9 protruding beyond one side face 10 of the disc 5; a log or slab feed hopper having a downwardly inclined delivery spout

11 directed toward the disc face 10 on one side of the axis of the rotor shaft 6; a wedge lock bar 12 normally coacting with each knife blade 8 within its confining slot 7, to clamp the adjoining knife in operative position; an elongated holding member or plate 13 firmly attached to the other rotor disc face 14 adjacent to each slot 7 and wedge bar 12, by means of cap screws 15; a number of adjusting screws, not shown, normally coacting with each plate 13 and with the blunt rear end of the adjacent blade 8; and a number of locking screws 16 coacting with each wedge bar 12 and with the adjacent holding plate 13 to firmly clamp the adjacent blade 8 in cutting position.

The rotor discs 5 may be of any desirable diameter and may be provided with any suitable number of slots 7 and knives 8, and these knife carrier discs are normally rotatable at high speed in the direction of the arrow shown in Fig. 3, so as to rapidly revolve the successive knife blades 8 past the feed spout discharge opening. The blades or knives 8 are constructed of durable metal, but because of the heavy duty which these cutting blades perform, they must be frequently removed for regrinding of the cutting edges 9, or for renewal after repeated sharpening. As clearly indicated in Fig. 3, the successive knives 8 are not readily accessible at the zone of the feed spout 11 unless this spout is removed with considerable difficulty, but the blades are freely accessible at all times at the opposite side of the rotor shaft 6, remote from this feed spout 11. During normal operation of the chipper, the knife blades 8 are clamped firmly against the inclined bounding surfaces 17 of the rotor slots 7 by the adjacent wedge bars 12 and locking screws 16, and these screws must be released in order to loosen the knives and to permit them to be withdrawn from their confining openings or slots.

In accordance with prior practice, it was customary to release the blade locking wedges, whenever a knife blade was to be removed, and to thereafter either utilize slow acting jack screws applied to the rear blunt end of the blade to lift it forwardly part way out of its confining slot, or to remove the blade holding plate so as to permit the knife to be withdrawn rearwardly from within its confining opening. Both of these methods were extremely tedious, and consumed a great deal of time, and they were also exceedingly dangerous when heavy blades or knives were being handled in connection with larger units.

In accordance with my present improvement, removal and insertion of the knife blades 8 is greatly facilitated and expedited, by providing each of the opposite ends of each blade 8 with a series of alined detents 18, and by also providing the opposite ends of each holding plate 13 with alined sockets 19, see Figs. 1 and 3. The reason for providing several sets of alined detents 18 in each blade 8, is to make the successive sets available as the blade is ground down during re-sharpening thereof. I additionally provide each elongated plate 13 with several parallel holes 20; and when it becomes desirable to remove a knife 8, the blade which is to be withdrawn should be positioned to the left of the central shaft axis and pointing upwardly as shown in Figs. 3 and 1 respectively.

After releasing the wedge bar 12 by loosening the locking screws 16 thereof, I apply to the pivot sockets 19, a U-shaped yoke or jack carrier 21 having axially adjustable pivot pins 22 carried by the free ends of the arms of the yoke and adapted

to swingably coat with the alined sockets 19. A transverse bar 23 having parallel pins 24 which are slidably cooperable with the holes 20 of the adjacent plate 13 and which are adapted to contact the lower blunt end of the corresponding blade 8, is then positioned between the side arms of the yoke 21, and a hydraulic jack 25 is disposed centrally between the bar 23 and the lower parallel cross-bar of the U-shaped carrier 21, see Figs. 1, 3 and 4. The hydraulic jack 25 may be of any conventional type, comprising a cylinder 26 having an oil supply reservoir therein and a base 27 firmly attached to the carrier 21 as by welding, a plunger 28 slidable within the cylinder 26 and adapted to engage the transverse bar 23, a small manually operable pump 29 carried by the base 27 and being operable to force liquid from the supply reservoir to the displacement chamber beneath the plunger 28, and a by-pass valve 30 for permitting free return of the liquid from the displacement chamber to the supply reservoir whenever the plunger 28 is being lowered. It will be apparent, that by operating the jack 25 so as to elevate the plunger 28 thereof after the screws 16 have been loosened, the corresponding knife blade 8 may be forcibly lifted or elevated as illustrated in Figs. 1 and 4 so as to cause its sharpened or cutting edge 9 to move outwardly beyond the disc surface 10 any desired distance.

I also provide an improved blade clamping and handling tongs 31 such as shown in Figs. 1 and 2, for the purpose of effecting safe withdrawal of the loosened blades 8, and reinsertion thereof within the openings 7 of the rotor 5. These tongs 31 consist of a pair of similar hook elements 32 pivotally interconnected by means of a central pivot pin 33 and having their lower ends provided with points 34 adapted to engage the several sets of alined notches or detents 18 formed in the blades 8, while their upper ends are connected by swingable links 35 with a suspension ring 36 which is adapted to coat with the hook of an ordinary overhead crane in an obvious manner. When the hook elements 32 are applied to a knife 8 as illustrated, and pulling or lifting force is applied to the ring 36, the points 34 will be driven into the detents 18 and the blade 8 will be firmly and safely suspended, but as an additional precaution, I may also provide a locking latch 37 swingably mounted upon one of the elements 32 by means of a pivot 38 and cooperable with a pin 39 on the other, in order to positively lock the blade 8 within the tongs 31, see Fig. 3.

While the mode of utilizing the relatively simple apparatus during the commercial exploitation of my improvement, should be quite clearly apparent from the foregoing detailed description, a short résumé of my improved system of removing and inserting chipper blades, will be given. When it becomes desirable to remove a knife 8 for regrinding or replacement, the worn knife blade should be positioned as shown in Fig. 3 on the side of the shaft 6 remote from the feed spout 11, whereupon the blade adjusting screws should be removed from the holes 20 if no special holes have been provided, and the adjusting screws 16 should be loosened so as to release the wedge bar 12. The yoke 21 having the jack 25 secured thereto should then be suspended by means of the pivot pins 22 from the sockets 19 of the holding plate 13, and the cross-bar 23 with its parallel pins 24 should be applied to the holes 20 in the plate 13. The yoke 21 and jack 25 may

then be swung into alignment with the bar 23 and pins 24, after which the pump 29 may be operated to cause the plunger 28 to move upwardly within the jack cylinder 26 and to raise the cross-bar 23 and the pins 24. Continued operation of the jack 25 will cause the pins 24 to force the knife blade 8 upwardly and to simultaneously slightly elevate the wedge bar 12 so as to free the blade 8 from lateral clamping pressure. As the blade 8 becomes elevated sufficiently so as to expose the uppermost set of detents 18 therein, the clamping tongs 31 may be applied to these exposed detents or notches, and the blade 8 may thereafter be freely lifted from within the confining slot of the opening 7 with the aid of a crane applied to the ring 36. After the blade has been resharpened and is ready for reinsertion within the rotor 5, or in case a new blade 8 is to be inserted, the blade may again be brought into approximate position relative to the rotor 5 and it may be swung about the holding points 34 of the clamping tongs 31 so as to cause the lower blade end to enter the slot between the wedge block 12 and the rotor surface 17. Continued lowering of the blade will then cause it to slide into proper position, it being necessary of course to first lower the pins 24 with the aid of the by-pass valve 30 of the jack 25. The yoke 21 together with the jack 25, and the bar 23 together with its pins 24 may then be removed and the blade 8 may be subsequently again firmly clamped within the rotor 5 after it has been properly located with its cutting edge 9 protruding from the side surface 10 of the rotor. In this manner, the knife blades 8 of the rotor 5 may be quickly and safely removed or inserted, with minimum loss of time and without danger of injuring the operator. As the blades 8 become worn and are reground, the successive side detents 18 will become effective for removal and insertion of the blades until they are sufficiently worn so as to make them unsatisfactory for further use.

From the foregoing detailed description of my improved apparatus for handling chipper blades or knives, it will be apparent that the present invention does in fact provide a system for safely and effectively removing and inserting these blades. The several successive steps involved can be quickly and expeditiously performed with the aid of relatively simple and inexpensive mechanism, thereby preventing excessive loss of time in reconditioning or renewing the knives 8, and at the same time insuring utmost safety in the handling of the relatively sharp and heavy blades. With the aid of my improved apparatus for handling chipper blades, it is unnecessary to completely remove the normal clamping mechanisms, and it is also unnecessary to undesirably modify standard blade holding assemblies and knife blades. The improved apparatus is adapted to be quickly applied and removed, and the handling tongs 31 may either be manipulated by hand or with the aid of an ordinary crane so as to expedite the removal and reinsertion of the cutting blades 8 without disturbing the feed hopper spout 11 of the chipper.

It should be understood that it is not desired to limit this invention to the exact details of construction of the apparatus or to the precise steps of the method, herein shown and described, for various modifications within the scope of the appended claims may occur to persons skilled in the art.

I claim:

1. A blade removing assemblage for a wood chipper having a rotary disc provided with a slot and a flat blade normally confined within the slot, an elongated blade holding plate secured to the disc near the slot and rearwardly of the blade, said plate having an opening therethrough directed toward the blunt end of the blade and also having aligned pivots associated with its opposite ends, the assemblage comprising, a U-shaped yoke having opposite side arms swingably suspended from said plate pivots and also having a jack mounted thereon between said side arms, and a cross-bar slidably confined between said yoke arms and having a pin movable through said plate opening toward said blade by coaction with said jack to eject the blade from its confining slot.

2. A blade removing assemblage for a wood chipper having a rotary disc provided with a slot and a flat blade normally confined within the slot and provided with aligned notches at each of its opposite ends, an elongated blade holding plate secured to the disc and spanning the disc slot rearwardly of the blade, said plate having a pair of parallel openings therethrough directed toward the blade and also having aligned pivots associated with its opposite ends, the assemblage comprising, a U-shaped yoke having opposite side arms swingably suspended from said plate pivots and also having a jack mounted thereon between said side arms, a cross-bar slidably confined between said yoke arms and having pins movable through said plate openings toward said blade by coaction with said jack to eject the notched side portions of the blade from the slot, and a pair of tongs cooperable with the exposed blade notches to completely withdraw the blade from the slot.

3. A blade removing assemblage for a wood chipper having a rotary disc provided with a slot and a flat blade normally confined within the slot, an elongated blade holding plate secured to the disc and spanning the disc slot rearwardly of the blade, said plate having a pair of laterally spaced parallel openings therethrough directed toward the blade and also having aligned pivots associated with its opposite ends, the assemblage comprising, a U-shaped yoke having opposite side arms swingably suspended from said plate pivots and also having a hydraulic jack mounted thereon midway between said plate openings, and a cross-bar slidably confined between said yoke arms and having parallel pins movable through said bar openings by coaction with said jack to eject the blade from its confining slot.
